UNITED STATES PATENT OFFICE.

SAMUEL G. CROSSLEY, OF PHILADELPHIA, PENNSYLVANIA, ASSIGNOR OF ONE-HALF TO FRANK A. WUNDER, OF PHILADELPHIA, PENNSYLVANIA.

LOCOMOTIVE-BOILER.

SPECIFICATION forming part of Letters Patent No. 699,791, dated May 13, 1902.

Application filed October 21, 1901. Serial No. 79,323. (No model.)

To all whom it may concern:

Be it known that I, SAMUEL G. CROSSLEY, a citizen of the United States, residing in the city and county of Philadelphia, State of Pennsylvania, have invented a new and useful Improvement in Locomotive-Boilers, of which the following is a specification.

My invention consists of an improved locomotive-boiler wherein the construction of the same is greatly simplified, provision being made for an increased heating-surface, whereby the heat units are utilized to the fullest extent, means being also provided so that a rapid circulation throughout all parts of the boiler is effected, whereby steam is generated in a rapid and effective manner.

It further consists of novel details of construction, all as will be hereinafter fully set forth, and particularly pointed out in the claims.

Figure 1 represents a longitudinal sectional view of a locomotive-boiler embodying my invention. Fig. 2 represents a section on line xx , Fig. 1. Fig. 3 represents a section on line yy , Fig. 1.

Similar numerals of reference indicate corresponding parts in the figures.

Referring to the drawings, 1 designates a locomotive-boiler, the same consisting of the outer shell or casing 2, in the front portion of which is formed the fire-box 3, within which is located a grate of the usual construction.

4 designates a fire-box door, above which extends longitudinally throughout the fire-box the water-circulating tubes 5, which may be of any number or diameter and which are preferably deflected at their rear portions and form communication between the front water-leg 6 and the rear water-leg 7 of the fire-box, it being understood that the water-legs 6 and 7 are in communication with the water-legs 8, (seen in Fig. 2,) so that the fire-box is surrounded by water at all times.

9 designates a combustion-chamber, in the upper portion of which, above the longitudinally-extending water-tubes 5, are located the transverse tubes 10, which, it will be noted, are arranged in staggered order, each row of tubes being inclined alternately, as will be

understood from the sectional view seen in Fig. 2.

11 designates the flue, which extends longitudinally through the boiler and forms a communication from the combustion-chamber 9 to the smoke-box 12, with which communicates the smoke-stack 13.

14 designates a series of water-tubes which extend in a vertical direction from the lower tube-sheet 15, which latter is preferably curved or arc-shaped, as indicated in Fig. 3, it being noted that said tubes 14 are arranged so that the tubes in the center of the boiler stand substantially upright, while the tubes on either side thereof have a greater outward inclination, the upper extremities of said tubes 14 being suitably secured in the curved upper portion or tube-sheet 16 of the flue 11.

It will thus be seen from the foregoing that by reason of the tubes 14 a communication is formed between the lower water-chamber 17 and the upper steam-chamber 18, which communicates with the main steam-chamber proper, 19, from which steam may be conducted to the cylinders 20 in the usual manner. It will thus be apparent that by the provision of the longitudinally-extending water-tubes 5, which are located above the grate, provision is made for a positive circulation in the front water-leg 6 and the rear water-leg 7, and by the provision of the transverse water-tubes 10, arranged in the manner shown, means are provided for effecting the circulation between the water-legs 8 at the sides of the boiler, and it will furthermore be apparent that by locating the water-tubes 14 in the position shown a free and unimpeded circulation will be permitted between the chambers 17 and 18 and that, furthermore, since these tubes 14 are subjected to the action of the hot gases as the latter pass from the combustion-chamber to the smoke-box of the boiler there is no appreciable loss of heat and the products of combustion are utilized to their fullest extent.

It will be apparent that various changes may be made by those skilled in the art which will come within the scope of my invention, and I do not, therefore, desire to be limited

in every instance to the exact construction I have herein shown and described.

Having thus described my invention, what I claim as new, and desire to secure by Letters 5 Patent, is—

1. In a locomotive-boiler, water fire-box, a plurality of longitudinally-extending water-tubes joining the front and rear portions of said water fire-box, a plurality of transversely-
10 arranged water-tubes arranged in series and having different inclinations joining the sides of the fire-box, and located above said longitudinally-extending tubes, a flue leading from the combustion-chamber to the smoke-
15 box, and water-tubes located in said flue.
2. A locomotive-boiler consisting of a water fire-box, a plurality of longitudinally-extending water-tubes joining the front and rear legs of said water-box, the rear extremities of said
20 tubes being deflected downwardly, a plurality of transverse water-tubes located in the combustion-chamber above said longitudinally-extending tubes, said transverse tubes being arranged in series and having different
25 inclinations each series inclined in opposite directions, a flue leading from the combustion-chamber to the smoke-box of the boiler, and water-circulating tubes located in said flue.
3. A locomotive-boiler consisting of water fire-box surrounding the combustion-chamber, a plurality of longitudinally-extending water-tubes joining the front and rear legs of said water-box, the rear extremities of said
30 tubes being deflected downwardly, a plurality of transverse water-tubes located in the combustion-chamber above said longitudinally-extending tubes, said transverse tubes being arranged in series and having different
35 inclinations, a flue leading from the combustion-chamber to the smoke-box of the boiler,
40

and water-circulating tubes located in said flue, the lower portion of said flue being arc-shaped and serving as a tube-sheet for the reception of the lower ends of said water-tubes. 45

4. In a locomotive-boiler, the combination of a water fire-box, a plurality of longitudinally-extending tubes extending between the front and rear portions of said fire-box, a series of transversely-extending tubes located
50 in the combustion-chamber above said longitudinally-extending tubes, said transverse tubes being longitudinally inclined and arranged in staggered order, a flue leading from said combustion-chamber to the smoke-box, 55 the lower portion of said flue being arc-shaped and the upper portion of said flue being also curved, and water-tubes joining the upper and lower portions of said flue, the central water-tubes being substantially vertical 60 and the outer water-tubes having a greater inclination outwardly than said central water-tubes.

5. In a boiler, a water fire-box, a plurality of longitudinally-extending tubes, located between the front and rear portions of said fire-box, a series of transversely-extending tubes, located in the combustion-chamber above said longitudinally-extending tubes, said transverse tubes being in series and each series inclined in opposite directions, a flue leading from said combustion-chamber to the smoke-box, and water-tubes joining the upper and lower portions of said flue, the central water-tubes being substantially vertical and the 75 outer water-tubes having a greater inclination outwardly than said central water-tubes. 70
